GLASS WASHER

Thomas H. Corbett, Chicago, Ill.

Application May 7, 1957, Serial No. 46,057

Term of patent 14 years

(Cl. D49—2)

Fig. 1

Fig. 2

Fig. 1 is a perspective view of a glass washer showing my new design, and

Fig. 2 is a perspective view of the opposite side thereof, the end not shown being the same in appearance as the end shown except for an opening for a cord in the base.

The cord fragment shown is for illustrative purposes only.

I claim:

The ornamental design for a glass washer, substantially as shown and described.
